(57) **CLAIM**

The ornamental design for an industrial model of exercise equipment for ski simulation, as shown and described.

DESCRIPTION

FIG. 1 is a front view of the industrial model of exercise equipment for ski simulation;

FIG. 2 is a rear view of the industrial model of exercise equipment for ski simulation;

FIG. 3 is a left side view of the industrial model of exercise equipment for ski simulation;

FIG. 4 is a right side view of the industrial model of exercise equipment for ski simulation;

FIG. 5 is a top view of the industrial model of exercise equipment for ski simulation;

FIG. 6 is a bottom view of the industrial model of exercise equipment for ski simulation;

FIG. 7 is a left front perspective view of the industrial model of exercise equipment for ski simulation;

FIG. 8 is a right front perspective view of the industrial model of exercise equipment for ski simulation;

FIG. 9 is a left rear perspective view of the industrial model of exercise equipment for ski simulation; and,

FIG. 10 is a right rear perspective view of the industrial model of exercise equipment for ski simulation.

The broken lines shown in FIG. 6 of the industrial model of exercise equipment for ski simulation are included for the purpose of illustrating portions of the article and form no part of the claimed design.
